UNITED STATES PATENT OFFICE.

EDWARD T. CAMENISCH, OF CHICAGO, ILLINOIS.

RECEPACLE ATTACHMENT FOR BEDSTEADS.

1,357,951.

Specification of Letters Patent.

Patented Nov. 9, 1920.

Application filed April 9, 1920. Serial No. 372,638.

To all whom it may concern:

Be it known that I, EDWARD T. CAMENISCH, a citizen of the United States of America, and a resident of Chicago, county 5 of Cook, and State of Illinois, have invented certain new and useful Improvements in Receptacle Attachments for Bedsteads, of which the following is a specification.

This invention relates to means for providing 10 storage accommodations on the under-side of a bed, and more particularly to receptacle attachments of this character adapted for ready connection to ordinary bedsteads. The main objects of the invention 15 are to provide such a receptacle attachment positioned to clear the bed-spring, and capable of ready connection to and removal from a bedstead of the usual construction having side rails; to provide a 20 storage attachment of drawer-like character capable of being pulled forward readily for access to the interior and adapted to be effectually concealed by the bed when restored to its normal position; and to provide 25 an improved form of track and supporting means for the receptacle.

An illustrative embodiment of this invention is shown in the accompanying drawings, in which—

30 Figure 1 is a perspective view of a bedstead with the attachment in place, part of the bedstead being broken away, as will be understood.

Fig. 2 is a perspective view of one of the 35 tracks whereon the receptacle is reciprocatingly mounted.

Fig. 3 is a perspective view of an intermediary support or side bar.

Fig. 4 shows a vertical cross-section of 40 the bedstead with the attachment in end elevation, the receptacle being in its forward position and the cover partly raised.

Fig. 5 is a fragmentary vertical sectional view on the line 5—5 of Fig. 1.

45 In the construction shown in the drawings, the attachment 1 as a whole is secured to the bedstead 2, being suspended from the under side thereof. Said attachment comprises a pair of tracks 3 having upturned 50 ends adapted for attachment to the side rails 4, and a receptacle 5 mounted reciprocatingly on said tracks for movement forward and backward to positions of accessibility and concealment respectively.

55 Said receptacle is box-like in character and is provided with downwardly facing

shouldered supporting means 6 in the form of flanged bars or brackets disposed one at each end, where they are fastened by screws or the like. Said brackets 6, though adapted to ride directly on the tracks 3, are carried on intermediate truck-like means 7.

Each of the trucks 7 includes a rectangular bar 8 disposed horizontally with one of its edges 9 facing upwardly to serve as a track for the member 6, and with its other edge 10 disposed downwardly to bear upon the supporting means 11 hereinafter described. The rear end of said bar is provided with a downward projection 12 whereby an L-shaped bracket results. The upper and lower edges of said bar are provided with rollers 13 and 14. Another roller constituting the supporting means 11 is provided at the front end of track 3. The front end of bar 7 has an upward stop member 15 for arresting the members 6 and so limiting the forward movement of the receptacle 5.

The support 6 as shown in Fig. 1 is substantially Z-shaped in cross-section and is disposed with its upward flange 16 against the end of the box 5 and with its lower flange 17 extending downward outside of the carriage bar 7. Rollers 18 are pivoted to the downward flange whereby movement of the box on said member 7 is substantially frictionless. Rollers 18' may well be secured to the box to bear against the underside of the bar 8 to prevent tilting of the box. In Fig. 5 the box supports are more nearly of inverted channel shape, as indicated at 6'.

Each of the tracks 3 comprises a plurality of sections, two being shown in this instance, namely, a short rear section 19 and a forwardly disposed main section 20, both fitting at their overlapping ends in a common guide member 21 in which they are slidably mounted for adjusting the length of the track according to the width of the bedstead. The front section is provided with an upwardly turned arm 22 having a horizontal bearing 23 at its upper end for resting on the rail 4. The rear section has a similar arm 24 having a horizontally disposed tip 25 to rest on the rear rail of the bedstead. Fastening means are provided on each of said arms comprising a thumb screw 26 mounted in a horizontal bearing 27 on the outer side of the arm, so that upon turning the screw in one direction the

rail 4 is clamped between the track bearing tip and said screw.

The box 5 is preferably closed dust-tight, and for this purpose is provided with a lid 5 having hinges 29 at its rear edge. Said lid is preferably jointed foldably so as to give access to the front of the box when it is pulled forward only a short distance, and for this purpose is provided with a hinge 10 30 near the center. In order to facilitate drawing the box forward, a handle or pull 31 is provided on the front side.

The operation of the device is as follows: In order to gain access to the box the operator 15 grips the handle 31 and pulls forward to a greater or less degree, depending on whether it is desired to raise the entire lid or only the front half. As the box moves forward there is first relative movement between 20 either the box 5 and the carriage 7, or the carriage 7 and the track 3, after which there is relative movement between the carriage 7 and the other member relative to which motion has not already occurred. 25 As soon as the box is pulled forward sufficiently the front half of the lid may be folded over on the rear half and then the rear half may swing, carrying with it the front half, as will be understood. In order 30 to close the device and restore same, the reverse operation is followed. In fitting the device to a bed the tracks 3 are first applied to the bed rails 4 in suitably spaced relation to accomodate the box 5, whereupon the 35 box is set in place substantially as shown in Fig. 1.

Although but one embodiment of the main features of this invention is herein shown and described, it is to be understood that numerous details of the construction 40 shown and described may be altered or omitted without departing from the spirit of this invention as defined by the following claims.

45 I claim:

1. A bedstead attachment of the character described comprising a receptacle in combination with a pair of depending track members adapted to support said receptacle 50 on the side-rails of a bedstead with ample clearance for the bedspring, said members each having a bearing near its front end, and said receptacle having a pair of supports secured directly thereto and a pair of 55 bars whereon said supports are slidable,

said bars being slidable on said track members respectively, said bearings serving as front supports for said bars, and said bars having bearings at their rear end for engaging said track members on its upper and 60 under sides respectively.

2. An attachment of the character described comprising a receptacle in combination with a pair of U-shaped track members adapted to support said receptacle on the 65 side-rails of a bedstead with ample clearance for the bedspring, said members each having a roller pivoted near its front end, and said receptacle having a pair of supports secured directly thereto and a pair of 70 bars whereon said supports are slidable, said bars being slidable on said track members respectively, said rollers serving as front bearings for said bars, and said bars having rollers pivoted thereto at their rear 75 end for engaging said track members.

3. An attachment of the character described comprising a receptacle in combination with a pair of depending track members adapted to support said receptacle on the side-rails of a bedstead with ample clearance for the bedspring, said members, each having a bearing near its front end, and said receptacle having a pair of supports secured directly thereto, and a pair of bars 85 whereon said supports are slidable, said bars being slidable on said track members respectively, said bearings serving as front supports for said bars and said bars having bearings at their rear ends for engaging 90 said track members and shoulders at their front ends to limit the travel of said supports.

4. A bedstead in combination with a drawer-like receptacle, means secured to the 95 bedstead for slidably supporting said receptacle, and a jointed foldable cover hinged at its rear edge to the back part of said receptacle, said cover being foldable wholly or in part to more or less open the receptacle when it is advanced on said supporting means, the front section of said cover being adapted and arranged to be opened first, and to be swung back upon the adjacent section which may then be swung carrying 100 with it the first mentioned section.

Signed at Chicago this 5 day of April, 1920.

EDWARD T. CAMENISCH.
